(57) CLAIM

The ornamental design for a pajamas as shown and described.

DESCRIPTION

1. Pajamas

1.1: Front

1.2: Back

1.3: Top

1.4: Bottom

1.5: Right

1.6 : Left

1.7 : Reference 1

1.8 : Reference 2

1.9 : Reference 3

1.10 : Reference 4

The design is pajamas; coating materials of some elements of the pajamas, for example, tapes, printed patterns, may contain minerals (e.g. powdered healing crystals); in the reproductions, the areas shown in solid lines are the areas for which protection is sought; the broken lines in the reproductions depict portions of the pajamas that form no part of the claimed design; reproductions 1.7, 1.8 are reference views showing the state of use and do not form part of the claimed designs; reproductions 1.9, 1.10 show front/back reference views where the diagonal lines indicate the areas where mineral is present and do not form part of the claimed design; the diagonal lines shown in reproductions 1.9 and 1.10 form no part of the claimed design.

1 Claim, 10 Drawing Sheets
